UNITED STATES PATENT OFFICE.

ARNOLD P. MASON, OF FRANKLINVILLE, NEW YORK, ASSIGNOR TO
WILLIAM H. BARD.

IMPROVEMENT IN CHECK-REIN SWIVELS.

Specification forming part of Letters Patent No. 115,224, dated May 23, 1871.

To all whom it may concern:

Be it known that I, ARNOLD P. MASON, of Franklinville, in the county of Cattaraugus and State of New York, have invented a new and useful Improvement in Check-Rein Swivel; and I do hereby declare that the following is a full, clear, and exact description thereof, which will enable others skilled in the art to make and use the same, reference being had to the accompanying drawing forming part of this specification.

This invention relates to a new and useful improvement in mode of adjusting and supporting bridle check-reins; and consists in a movable loop or swivel for the check-rein, connected with a buckle-frame and arranged to operate as hereinafter described.

In the accompanying drawing, Figure 1 is a front view, showing the loop or swivel attached as when in use. Fig. 2 is a longitudinal section of Fig. 1 on the line *x x*.

Similar letters of reference indicate corresponding parts.

A is the loop or check-rein "swivel," which is attached to the end of the buckle B, as seen at C. D is a small plate connecting the two sides of the buckle, on the side of which plate

is a small lug or pin, E, immovable on the plate, but which acts as the tongue of the common buckle, as it passes through one of the holes in the strap to which it is attached, as seen in Fig. 2.

The buckle and loop, connected together and forming the check-swivel, are intended to be buckled onto the throat-latch "billet" close up to the front piece of the bridle.

The end of the loop A is confined under the cross-bar F of the buckle, but it is readily drawn down from that position when the check-rein is to be inserted, there being sufficient flexibility or elasticity in the loop to allow of this.

Having thus described my invention, I claim as new and desire to secure by Letters Patent—

The loop or check-swivel A and buckle B, constructed, arranged, and operating substantially as and for the purposes herein shown and described.

ARNOLD P. MASON.
